DISPOSABLE RAZOR

Alexander Samko, New York, N. Y., assignor of
one-third to Joseph Masip and one-third to
Arthur Gandon, both of New York, N. Y.

Application March 20, 1952, Serial No. 277,605

1 Claim. (Cl. 30—32)

1

This invention relates to shaving equipment, and more particularly to a safety razor.

The object of the invention is to provide a safety razor which is constructed in an inexpensive manner, so that the razor can be discarded after being used one or two times.

Another object of the invention is to provide a safety razor which has a razor blade permanently mounted therein, the razor and blade adapted to be discarded after being used one or two times, whereby a sanitary razor is provided at all times.

A further object of the invention is to provide a razor which is extremely simple and inexpensive to manufacture.

Other objects and advantages will be apparent during the course of the following description.

In the accompanying drawings forming a part of this application, and in which like numerals are used to designate like parts throughout the same:

Figure 1 is a front elevational view of the razor, constructed according to the present invention;

Figure 2 is a side elevational view of the razor;

Figure 3 is a top plan view of the razor;

Figure 4 is a bottom plan view of the razor;

Figure 5 is an enlarged sectional view taken on the line 5—5 of Figure 1;

Figure 6 is an enlarged sectional view taken on the line 6—6 of Figure 5;

Figure 7 is a plan view of the blank from which the razor is formed;

Figure 8 is a plan view of the blade used in the razor.

Referring in detail to the drawings, the numeral 10 designates the razor which is preferably fabricated of a single piece of suitable material, such as thin metal, and the razor 10 includes a handle 11 which is preferably tubular and cylindrical in shape. Extending from one end of the handle 11 is a flat section 12, and arranged at right angles with respect to the flat section 12 and projecting therefrom is a holder 14, Figure 5.

The holder 14 includes a top wall 15, and arranged below the top wall 15 is a pair of spaced tongues or clips 16 and 16', Figure 4. The tongues 16 and 16' coact with the top wall 15 to retain or hold therein a razor blade 17, Figure 8, the razor blade 17 being provided with a sharp cutting edge 18.

2

The holder 14 is provided with a slot 19 which enables the cutting edge 18 of the razor blade 17 to perform its normal cutting function. Thus, by gripping the handle 11 and moving the razor 10 along the face or other part of the body being shaved, the portion of the cutting edge 18 exposed by the slot 19 will effectively cut the hairs from the face. Arranged transversely with respect to the top wall 15 and projecting therefrom is a guard bar 20, the guard bar 20 serving to help maintain the blade 17 in its proper place in the holder 14, and the guard bar 20 also serving to prevent the user from being accidentally cut by the blade 17.

15 Referring to Figure 7, there is shown the blank for forming the razor of the present invention. The blank of Figure 7 includes the flat section 12 and the pair of tongues 16 and 16'. These tongues 16 and 16' are adapted to be bent about the crease line 21, Figure 7, after the blade 17 has been properly positioned therein, so that the tongues 16 and 16' will coact with the wall 15 to maintain the razor blade in its proper position. Also, the guard bar 20 is adapted to be folded 20 or bent along the crease line 22, Figure 7, so that the guard bar 20 occupies the position shown in Figures 1 through 6.

25 From the foregoing, it is apparent that a razor has been provided, the razor having a blade permanently mounted therein, so that after the razor has been used one or two times, the entire razor and blade can be discarded. The razor 10 can be easily formed from the blank illustrated in Figure 7, so that the cost of manufacture is 30 extremely small. Therefore, the razor can be discarded without placing an undue financial burden on the user. Also, the construction of the tongues, top wall and guard bar insures that the user will be able to effectively shave himself 35 without having the blade slip from the holder, or without danger of accidentally cutting himself. The blade cannot be changed, so that the razor is advantageous from a sanitary point of view.

40 I claim:

45 In a disposable razor adapted to be discarded after being used several times, said razor being fabricated of a single piece of material and including a tubular handle, a flat section projecting from one end of said handle, a holder extend-

ing from such flat section and arranged at right angles with respect thereto, said holder being provided with a slot in its front end, said slot having its ends terminating short of the ends of said holder, said holder adapted to confine a razor blade therein and with the razor blade cutting edge arranged contiguous to such slot, a pair of tongues spaces below said holder for maintaining said razor blade in said holder, and a guard bar arranged transversely with respect to said holder and extending downwardly therefrom, said tongues having their front ends spaced

from said guard bar, said guard bar being arranged parallel to said flat section.
